[57] CLAIM

The ornamental design for a dual compartment bottle, as shown and described.

DESCRIPTION

FIG. 1 is a front elevation of a dual compartment bottle showing my new design; the rear elevation being a mirror image of front elevation;

FIG. 2 is a front elevation of a first modified form of FIG. 1, the rear elevation being a mirror image of the front;

FIG. 3 is a right side elevation FIG. 1;

FIG. 4 is a right side elevation of FIG. 2;

FIG. 5 is a left side elevation of FIGS. 1 and 2.

FIG. 6 is a top plan view of FIGS. 1 and 2;

FIG. 7 is a front elevation of a second modified form of FIG. 1, the rear elevation being a mirror image of the front;

FIG. 8 is a front elevation of a third modified form of FIG. 1, the rear elevation being a mirror image of the front;

FIG. 9 is a right side elevation of FIGS. 7 and 8;

FIG. 10 is a left side elevation of FIGS. 7 and 8;

FIG. 11 is a top plan view of FIGS. 7 and 8; and

FIG. 12 is a bottom plan view of FIGS. 1, 2, 7, and 8.
